UNITED STATES PATENT OFFICE.

VINCENZO GARREFFA, OF GENEVA, OHIO.

DESIGN FOR A SWING HOOK.

Application filed July 23, 1924. Serial No. 10,225. Term of patent 3½ years.

To all whom it may concern:

Be it known that I, VINCENZO GARREFFA, a subject of the King of Italy, residing at Geneva, in the county of Ashtabula and State of Ohio, have invented a new, original, and ornamental Design for Swing Hooks, of which the following is a specification, reference being had to the accompanying drawing, forming part thereof.

The figure is a perspective view of a swing hook, showing my new design.

I claim:

The ornamental design for a swing hook as shown.

In testimony whereof I affix my signature.

VINCENZO GARREFFA.
